DESIGN FOR A JUG

Henry G. McKnight, Toledo, Ohio, assignor to Owens-Illinois Glass Company, Toledo, Ohio, a corporation of Ohio

Application June 23, 1939, Serial No. 85,639

Term of patent 14 years

To all whom it may concern:

Be it known that I, Henry G. McKnight, a citizen of the United States, residing at Toledo, in the county of Lucas and State of Ohio, have invented a new, original, and ornamental Design for a Jug, of which the following is a specification, reference being had to the accompanying drawing, forming a part thereof.

In the drawing the figure is a side elevational view of a jug showing my new design, the characteristic feature of which is the particular neck and finish contour illustrated.

I claim:

The ornamental design for a jug, substantially as shown and described.

HENRY G. MCKNIGHT.
